UNITED STATES PATENT OFFICE.

JOHN HAYS HAMMOND, JR., OF GLOUCESTER, MASSACHUSETTS.

SYSTEM OF SELECTIVE CONTROL.

1,098,379.

Specification of Letters Patent.

Patented June 2, 1914.

Application filed September 7, 1911. Serial No. 648,225.

To all whom it may concern:

Be it known that I, JOHN HAYS HAMMOND, Jr., a citizen of the United States, residing at Gloucester, in the State of Massachusetts, have invented certain new and useful Improvements in Systems of Selective Control, of which the following is a specification.

My invention relates to a system of selective control and relates particularly to a system in which ether disturbances of predetermined frequencies are received selectively by the receiving station.

The principal object of the invention is to produce a system whereby the opening or closing of a local circuit may be controlled without liability to interference.

The various other objects of the invention will be more fully set forth in the following description of one form of apparatus suitable for practising the invention.

In the particular apparatus shown in the accompanying drawings for the purpose of illustrating the operation of my improved system, waves of light, having a plurality of fluctuations impressed thereon by a microphone, are emitted from the sending station and received by the selenium cell at the receiving station, but it will be obvious that any suitable means of propagating ether disturbances may be employed which will permit a plurality of fluctuations of predetermined frequencies.

In the drawings, Figure 1 is a diagrammatic view of one form of apparatus for carrying out my improved system. Fig. 2 is a corresponding view showing different connections in the receiving station.

In the particular apparatus shown in the drawings for the purpose of illustrating my improved system, a motor 1 drives a direct current generator 2 which feeds an arc lamp 3. In the arc lamp circuit are included resistance 4 and self-inductance 5 to steady the arc. The secondary 6 of a transformer is also included in this circuit, the primary of which transformer 7 is traversed by currents emanating from battery 8 and controlled by microphone 9. The microphone is acted upon by vibrations from a number of reeds 10, 11 and 12, which have their individual and fixed vibrating frequencies.

When the reeds are vibrated by means of any convenient method, they emit a chord of three definite frequencies which are reproduced by means of a microphone and varia-

tions of the microphone current. The transformer, whose primary is 7 and secondary 6, therefore produces alternating potentials at secondary 6 which produces in the arc circuit alternating currents of the three frequencies superimposed on the direct currents furnished by generator 2. The light emitted from the arc 3 has periodic increases and decreases governed by the alternating currents in the arc circuit.

A reflector 14 is arranged at the receiving station and is focused so as to concentrate a part of the light from the arc upon a selenium cell 15 in circuit 16 with a battery 17. Battery 17 will therefore send a current through circuit 16 which fluctuates very much the same as the conductivity of the selenium cell 15, the currents of circuit 16 being therefore of direct current with superimposed currents of the three frequencies. In circuit 16 are also included the three coils 18, 19 and 20, of the three vibratory relays 21, 22 and 23. The tuned reeds 24, 25 and 26, are mounted in proximity to the coils 18, 19 and 20; reed 24 having the same period of vibration as reed 10 of the transmitter; reed 25 having the same period of vibration as reed 11 of the transmitter; and reed 26 having the same period of vibration as reed 12 of the transmitter. Consequently, when the transmitter reeds 10, 11 and 12 are caused to vibrate, the receiving reeds 24, 25 and 26 will also be caused to vibrate and will attain an appreciable amplitude by virtue of resonance. Suitable means 27, 28 and 29 are arranged in circuit with polarized relays 30, 31 and 32 whereby appreciable vibrations of said receiver reeds will close said circuits to which current is furnished by suitable means as the batteries 33, 34 and 35. The armatures 36, 37 and 38 of the polarized relays will therefore be deflected to the right by making contact with points 39, 40 and 41 will close local circuits 42, 43 and 44 having batteries 45, 46 and 47 respectively which energize magnet coils 48, 49 and 50 respectively. Said magnet coils in turn attract armatures 51, 52 and 53 thus completing the local circuit 54 comprising a battery 55 which energizes the magnet coil 56. Said coil then draws armature 57 to contact 58 whereby any suitable means as the battery 59 is made to energize a plunger magnet coil or solenoid 60, which in turn actuates plunger 70 and thus controls any desired form of operative mechanism, such as a lever 72

connected with the plunger by any suitable connection as the chain 71.

In the modified form of apparatus shown for the purpose of illustration in Fig. 2, the sending station is represented as being identical to the sending station shown in Fig. 1 and the receiving station is provided with a selenium cell 15 in circuit 16 comprising the battery 17. In this construction, however, the corresponding coils 18', 19' and 20' are in multiple with the circuit 16. Coils 19' and 20', however, do not connect directly to the line wires 16^a and 16^b of the circuit 16 but depend for their final connection on the closing of armatures 51' and 52' with the contact points 73' and 74'. In this construction, variations of the conductivity of the selenium cell 15 causes battery 17 to send fluctuating currents to the coil 18' which through reed 24' and controlling means 27' actuates the polarized relay 30' and by means of relay coil 48' attracts armature 51' to a point 73'. Coil 19' is thereupon energized thereby energizing the vibratory reed 25' which, by the controlling means 28', operates a polarized relay 31' thus closing circuit 43' and energizing relay coil 49', the armature 52' of which connects coil 20' to the line wires 16^a and 16^b. Said coil 20' causes reed 26' to vibrate and through controlling means 29' operates the polarized relay 32', the armature 38' of which is connected to a point 41' thus closing the circuit 44' comprising the battery 47' which operates relay coil 50'. The armature 53' of said coil 50' then closes the local circuit 54', including the battery 55', in which the relay coil 56' is located. The armature 57' of this relay makes contact with point 58' thus permitting the battery 59' to energize plunger coil of solenoid 60', the plunger 61' of which is operatively connected by any suitable means as the chain 62' to the lever 63'.

In the construction shown in the drawings 45 conjoint action of the transmitter reeds 10, 11 and 12 is required to complete circuit 54, or circuit 54', respectively.

In the construction particularly shown in Fig. 1, reed relays are arranged in series, 50 whereas in Fig. 2, they are arranged in multiple, but in both cases conjoint action is required, thus rendering the system proof against interference except by the combined action of the three predetermined frequencies of fluctuation.

It will be obvious, of course, that various other means of producing the three predetermined frequencies may be employed, since it is well known that they can be produced 60 through sending station comprising various means for emitting either damped or undamped vibrations, and it will be understood that in illustrating the invention in connection with an apparatus employing 65 light waves, I have merely shown a pre-

ferred form of apparatus embodying my improved system.

I claim as my invention:

1. In a system of the character described, a receiving station adapted to receive light vibrations whose characteristics are such as to produce fluctuations of predetermined frequencies in the receiving station, said receiving station comprising means to respond to each of said fluctuations of different frequency and said means operating conjointly to close a local circuit. 75

2. In a system of the character described, a receiving station adapted to receive light vibrations having a plurality of fluctuations of predetermined frequencies, means for causing these fluctuations of predetermined frequency to produce appreciable vibrations of a plurality of receiving means, and means for controlling a local circuit through such receiving means. 80

3. In a system of the character described, a receiving station adapted to receive light vibrations having a plurality of fluctuations of predetermined frequencies, means for causing said fluctuations of predetermined frequency to produce simultaneously appreciable vibrations of a plurality of receiving means, and means for controlling a local circuit through such receiving means. 90

4. In a system of the character described, a receiving station adapted to receive light vibrations having a plurality of fluctuations of predetermined frequencies, means for causing the fluctuations of each frequency to produce appreciable vibrations of separate receiving means, and means for controlling a local circuit through the conjoint action of such receiving means. 100

5. In a system of the character described, 105 a receiving station adapted to receive ether vibrations having a plurality of fluctuations of predetermined frequencies, means for causing fluctuations of each frequency to produce appreciable vibrations of separate monotone vibrating relays, said relays being in parallel circuits and means for controlling a local circuit by the action of such relays. 110

6. In a system of the character described, 115 a receiving station adapted to receive ether vibrations having a plurality of fluctuations of predetermined frequencies, and comprising a plurality of monotone vibrating relays, said relays being arranged in parallel circuits, means for causing the fluctuations of each predetermined frequency to produce mechanical vibration of one of said relays, and means for controlling an independent local circuit through the conjoint action of 120 said relays. 125

7. In a system of the character described, a sending station comprising an arc, means for simultaneously impressing variations of a plurality of predetermined rates upon the

ether vibrations produced by said arc, a receiving circuit comprising a selenium cell to receive said ether vibrations having said predetermined variations impressed thereon, means for causing said variations to produce mechanical vibrations in a plurality of tuned relays, and means for controlling a local circuit through such relays.

8. In a system of the character described, a sending station comprising an arc producing ether vibrations, a microphone inductively coupled with said arc, and a plurality of acoustic pipes each capable of emitting a predetermined acoustic tone whereby a plurality of fluctuations of predetermined frequency are impressed on said ether vibrations, a receiving station comprising a selenium cell to receive said vibrations, and a plurality of monotone vibrating relays each responsive to the fluctuations produced by one of said pipes, and means for controlling a local circuit through such relays.

9. In a system of the character described,

a sending station comprising an arc producing ether vibrations, a microphone inductively coupled with said arc, and a plurality of acoustic pipes each capable of emitting a predetermined acoustic tone whereby a plurality of fluctuations of predetermined frequency are impressed on said ether vibrations, a receiving station comprising a selenium cell to receive said vibrations, a plurality of separate monotone vibrating relays each responsive to the fluctuations produced by one of said pipes and arranged in circuit with each other, a plurality of polarized relays in circuit with said vibrating relays, and an independent local circuit controlled by the conjoint action of said polarized relays.

This specification signed and witnessed this 1st day of September, A. D., 1911.
